(57) **CLAIM**

The ornamental design for a mug, as shown and described.

DESCRIPTION

FIG. 1 is a perspective view of a mug showing my new design;

FIG. 2 is another perspective view of the mug of FIG. 1; FIG. 3 is a left elevation view of the mug FIG. 1;

FIG. 4 is front elevation view of the mug of FIG. 1;

FIG. 5 is right elevation view of the mug of FIG. 1;

FIG. 6 is a rear elevation view of the mug of FIG. 1;

FIG. 7 is a top plan view of the mug of FIG. 1;

FIG. 8 is a bottom plan view of the mug of FIG. 1;

FIG. 9 is an exploded view of the mug of FIG. 1; and,

FIG. 10 is a cross section view of the assembled mug of FIG. 1.

The broken lines shown in the drawings are for illustrative purposes only and form no part of the claimed design.

1 Claim, 9 Drawing Sheets
